UNITED STATES PATENT OFFICE.

CHARLES FRANCIS JENKINS, OF WASHINGTON, DISTRICT OF COLUMBIA.

PRODUCING LIGHT-BEAMS.

1,390,445.

Specification of Letters Patent. Patented Sept. 13, 1921.

Application filed April 16, 1918. Serial No. 228,891.

To all whom it may concern:

Be it known that I, CHARLES FRANCIS JENKINS, a citizen of the United States, and resident of Washington, in the District of Columbia, have invented certain new and useful Improvements in Producing Light-Beams, of which the following is a specification; reference being had therein to the accompanying drawing.

10 In ordinary apparatus for forming a beam of light, for example, for signaling, or in picture projecting devices, most of the light generated is lost. To utilize most of this lost light so as to secure a much more-powerful beam from a given source, or to obtain a beam of a given strength while generating much less than the ordinary light, is the object of this invention.

For illustration apparatus suitable for 20 picture projecting has been selected.

The accompanying drawing shows such apparatus in vertical section through the axis of the light beam.

In this drawing, A represents an electric 25 lamp bulb containing a light source B, preferably of small area and with its broader faces transverse to the axis as usual in analogous apparatus. C is a plate provided with an aperture C' at which pictures to be projected are exposed, and D is a common projecting lens.

Slightly in front of the source B is a tubular reflector E of approximately parabolic form adapted to reflect rays F from the 35 source B so that they take the direction indicated at F' and, except an outer fringe of rays, pass through the aperture C' and meet at the lens D. Rays G passing rearward from the other broad face of the filament 40 strike a reflecting coating A' in the bulb and are thrown back to the center and like the rays F strike the reflector E and pass to the lens D. Rays H which fall within the angle of the dotted lines I, would naturally 45 fail to strike the reflector E and would fail to pass through the aperture C' and would be lost. For this reason, I place at a suitable

distance from the light source a thin lens J perpendicular to the beam's axis and of proper convexity to focus these rays at the 50 lens D.

The result of this arrangement is that a very small fraction of the generated light is lost. The zone between the mirror A' and the plane of the adjacent end of the reflector E receives only a small amount of light from the thin edge of the source B and the marginal loss at the periphery of the lens J and at the aperture C' is very slight.

Obviously, moving the bulb A along the axis varies the convergence of the rays, and of course the distance at which the lens D should be placed. Indeed, the rays F' may be made approximately parallel as in the 65 case of a common parabolic reflector. In doing this, the plate C and lens D may be omitted. When this is done, the apparatus still allows radiant heat to escape freely, both because it is radiated directly from the 70 bulb into the open air and because air passes through the reflector E.

The parabolic tube may be extended at its larger end without disadvantage, but at its smaller end it must throw no rays to the 75 lens J.

What I claim is:

The combination with a spherical electric light bulb, of an open approximately parabolic tubular reflector in position to receive 80 rays from the bulb and focus them approximately at a distant projecting lens, a plate interposed in the light beam and provided with an exposure aperture therefor, and a lens in the axis of the beam in position to 85 receive the rays directed centrally out of the larger end of the tubular reflector and adapted to focus them approximately at the projecting lens, said bulb being provided on the side most distant from the tubular reflector with a spherical reflecting surface.

In testimony whereof I hereunto affix my signature.

CHARLES FRANCIS JENKINS.
